CLAIM

We claim the ornamental design for a wireless headphone, as shown and described.

DESCRIPTION

FIG. 1 is a right side perspective view of a wireless headphone in accordance with the present invention;

FIG. 2 is a left side perspective view thereof;

FIG. 3 is a right side view thereof;

FIG. 4 is a bottom view thereof;

FIG. 5 is a front view thereof;

FIG. 6 is a rear view thereof;

FIG. 7 is a left view thereof;

FIG. 8 is a top view thereof;

FIG. 9 is a right side perspective view of a second embodiment of a wireless headphone in accordance with the present invention, the only differences being openings in the surface of the design and a release button are solid lines;

FIG. 10 is a left side perspective view of the design in FIG. 9;

FIG. 11 is a right side view of the design in FIG. 9;

FIG. 12 is a bottom view of the design in FIG. 9;

FIG. 13 is a front view of the design in FIG. 9;

FIG. 14 is a rear front view of the design in FIG. 9;

FIG. 15 is a left view of the design in FIG. 9; and,

FIG. 16 is a top view of the design in FIG. 9.

The broken lines depict portions of the wireless headphone that form no part of the claimed design.
